BOTTLE

James B. McGinnis, Burlingame, Calif., assignor
 to Paul Masson, Inc., Cupertino, Calif., a corporation of California

Application June 20, 1952, Serial No. 20,285

Term of patent 14 years

(Cl. D58—8)

To all whom it may concern:

Be it known that I, James B. McGinnis, a citizen of United States of America, residing at Burlingame, in the county of San Mateo and State of California, have invented a new, original, and ornamental Design for a Bottle, of which the following is a specification, reference being had to the accompanying drawing, forming part thereof.

Fig. 1 is a front elevational view of a bottle, showing my new design;

Fig. 2 is a side view thereof;

Fig. 3 is a top plan view thereof;

Fig. 4 is a rear view thereof; and

Fig. 5 is a partial sectional view taken along line 5—5 of Fig. 1.

I claim:

The ornamental design for a bottle, substantially as shown.

JAMES B. McGINNIS.
